UNITED STATES PATENT OFFICE.

EARL E. ADAMS, OF BATTLE CREEK, MICHIGAN.

CARBURETER.

No. 813,683.

Specification of Letters Patent.

Patented Feb. 27, 1906.

Application filed April 10, 1905. Serial No. 254,705.

To all whom it may concern:

Be it known that I, EARL E. ADAMS, a citizen of the United States, residing at Battle Creek, in the county of Calhoun and State of Michigan, have invented certain new and useful Improvements in Carbureters; and I do hereby declare the following to be a full, clear, and exact description thereof, such as will enable others skilled in the art to which

10 it appertains to make and use the same.

This invention relates to carbureters for gas-engines; and the object of this invention is to provide a device of its class that will be symmetrical and tasty in design, simple and 15 inexpensive in construction, and effective and reliable in operation; and it more particularly relates to carbureters for use on marine engines, where the center of gravity in the gasolene-supply thereto will not materially 20 vary by the tilting of the engine through the rock of the boat. However, the same may be readily attached to any of the ordinary portable gasolene-engines to the best of satisfaction.

25 Other objects and advantages will appear and the features of construction and peculiar combination of parts will be first described and then specifically pointed out in the appended claims, reference being had to the accompanying drawings, in which—

30 Figure 1 represents a vertical cross-section of my improved carbureter with the air-passages open, and shows the position of the vaporizing-spray nozzle in relation thereto. Fig. 35 2 is a vertical cross-section, quarter-angular to Fig. 1, taken through the air-inlet and vaporizing-outlet and shows the float feed-valve. Fig. 3 is a cross-section of Fig. 1 on the line $x-x$; and Fig. 4 is a cross-section of Fig. 1 on the line $z-z$, showing the shell A only.

40 In the drawings like marks of reference refer to corresponding parts throughout the different views.

A represents the shell or body portion to 45 my improved carbureter, and by preference the same is round with an indrawn bottom portion, as shown. Connecting with and forming part of the outer shell by means of a web B a secondary or inner shell C is provided. This shell has two compartments or 50 chambers, the one located above the other and separated by a diaphragm 1. This diaphragm has an opening 2, the central part thereof providing for the reception of the stand-pipe 10. The upper or vaporizing 55 chamber has an exhaust port or orifice 3 com-

municative with the engine proper, the lower chamber communicating with the atmosphere through the medium of an orifice 4, both of said orifices leading through the web 60 B of the carbureter. Within the bottom of the lower chamber a small waste-tube 5 is provided. This tube leads to the outside of the carbureter, and its object is to prevent any accumulation of sediment or overflow 65 accumulating within said chamber. This tube by preference is introduced within the mold and cast solidly within the carbureter. The indrawn portion of the bottom of the outer shell forms a trap within which a screw-plug 7 is introduced, and mounting the top of the carbureter a cap or cover D, having a central circular opening and a threaded depending outer flange, is provided, the flange of the cover being received by a threaded outer extremity of the shell A, as shown.

70 Between the outer and inner shells of the carbureter a chamber or reservoir E is formed. This chamber is the intermediate fluid or gasolene holding receptacle between the supply-tank and the engine, and its supply is controlled by means of a float 7, through which the stem of a vertical operating tapering valve 8 is provided. An opening 9, formed in the bottom of outer shell to 75 the carbureter and within which the valve 8 is adapted to play, provides a means for connecting the carbureter with a storage-tank.

80 Centrally within the bottom of the lower chamber to the inner shell C a threaded aperture is provided, and within the hole a feed stand-pipe 10 is screwed. The stand-pipe extends somewhat above the carbureter and is provided with a central opening, the bottom of which communicates with the gasolene-reservoir E, while its upper extremity is threaded and fitted with a needle-valve 11 of the usual construction.

85 At a point slightly above the orifice 2 in the diaphragm 1 and opening within an atomizing chamber or valve F the stand-pipe 10 is supplied with a spray-nozzle 12, whose mouth is upward, as shown. The valve F fits snugly and its walls are of a length extending from the diaphragm 1 to a point flush with 90 the upper end of the shell C, within which it is fitted. An orifice 13, very like in size and shape to the orifice 2 in the diaphragm 1, is made in the bottom thereof, and at the top of this chamber an externally-threaded neck 14 is provided, having a central hole through 95 which the stand-pipe 10 is adapted to fit.

Within the side of this valve an exhaust-port 15 is made and communicates with the engine-supply aperture 3, under control of the governor or throttle-lever to the engine, hereinafter set forth. This exhaust-port is large enough to permit the oscillating of the valve F and not close the aperture 3.

G is a throttle-controlling lever to the end 16 of which the governor or throttle-lever is attached in the usual manner for controlling an engine. This lever terminates in an annular collar 17, made of a size corresponding with the top of the valve-chamber F, and through this collar the neck of said valve is adapted to fit. Encircling the upper end of the neck 10 to said valve-chamber a threaded jam-ring 18 is run and is adapted to be screwed down to impinge the collar 17 aforesaid.

20 Mounted near the upper threaded extremity of the needle-valve 11 a lever 19 is fitted. This lever forms a yoke at its outer end and engages the throttle-controlling lever G. The opposite end of this lever is slotted and 25 is made to impress the needle-valve by means of a set-screw 20 passing through the slotted extremity, and at the upper extremity of the needle-valve a hand-wheel 22 is provided.

Between the lever 19 and the neck 10 of 30 the valve-chamber F a heavy coil-spring 21 is fitted. The object of this spring is to keep the carbureting-chamber F closely seated upon the diaphragm 1 of the inner shell C.

The float 7 may be made of any suitable 35 material for the purpose, as a pneumatic chamber or cork, the latter answering well for the purpose. That the same may be made to actuate the supply-valve 8 accurately under all conditions, I provide a guide 40 23, through which the upper extremity of valve-stem may play.

The operation of my improved carbureter in the main will have been apparent from the foregoing description. It is desirable that 45 the exit or opening 3 of the carbureter be attached as close to the intake-port of the engine as possible, for the reason that quicker action will be derived from the gases generated. The supply of gasolene is thence connected to the opening 9, whence the same 50 will rise in the chamber E and lift the float 7 until the valve 8 forms a seat and prevents the same from rising higher than a predetermined level below the spray-nozzle 12. The 55 lever G is connected to a throttle-lever or direct to the governor of an engine, as the case may be. The needle-valve having been screwed down to a seat and thence slightly opened, the vaporizing-valve chamber F is 60 oscillated sufficiently to allow its port 15 and its intake 13 to register with the exit 3 and intake 2, respectively, by which means the vacuum thus formed by the engine-piston will draw gasolene-vapor from the valve-chamber F. The mixture having been prop-

erly established, the screw 20 in the lever 19 is set, and so also the jam-ring to lock the carbureting chamber or valve F and the throttle-lever together, the oscillating of the throttle-lever controlling both the supply 70 of air and gas mixture to the engine, also the quantity of gasolene to be vaporized.

It will be seen that I have provided a carbureter both tasty in design and also very simple, symmetrical, and compact. The 75 vaporizing-chamber being located centrally within the same, the device is especially applicable to marine-engine service, the center of gravity in the stand-pipe 10 always keeping the gasolene at or about a normal level, 80 though the same be tilted considerably out of plumb.

Having therefore described my invention, what I claim as new, and desire to secure by Letters Patent, is—

1. In a carbureter, the combination of an encircling gasolene-reservoir, a float-controlled valve to supply said reservoir, a central chamber suspended within said reservoir, a diaphragm having an opening separating said chamber into an upper and a lower compartment, an air-valve operative on and adapted to vary the opening in said diaphragm, a spray-nozzle opening upward in close proximity to said opening in the upper compartment, an exhaust-port to said compartment, an air-inlet to the lower compartment, and means to control said valve and spray-nozzle, substantially as set forth.

2. The combination of an encircling gasolene-reservoir, a float-controlled tapering valve to supply said reservoir, a central chamber suspended within said reservoir, a stand-pipe leading from said gasolene-reservoir through the center of said chamber, a diaphragm having an opening separating 95 said chamber into an upper and a lower compartment, an air-valve operative on and adapted to vary the opening in said diaphragm, a spray-nozzle leading from said stand-pipe in close proximity to said opening in the upper compartment, an exhaust-port in said compartment, an air-inlet to the lower compartment and means to control said valve and spray-nozzle, substantially as set 105 forth.

3. In a carbureter, the combination with an encircling gasolene-reservoir, and a float-controlled valve to supply said reservoir, of a central chamber suspended within and forming a part of said reservoir, said chamber being separated into an upper and a lower compartment by means of an apertured diaphragm, an air-inlet communicative with the lower compartment and an exhaust-port 110 leading from said upper compartment, a valve operative on and adapted to open and close said apertured diaphragm, means to actuate said valve, a spray-nozzle communicative with said upper chamber at a point 115

above and in close proximity to the aperture in said diaphragm, a valve to control said spray, and a lever to control said valve, for the purpose set forth.

5. 4. In a carbureter, the combination with an air-chamber, of a vaporizing-chamber, an air-passage connecting said chambers, a valve adapted to vary the opening to said air-passage between said chambers, a stand-pipe leading through said chambers, a spray-nozzle leading from said pipe and opening above said air-passage within said vaporizing-chamber, an arm on said valve, a needle-valve in the stand-pipe, to control the gas-forming fluid, a clamp carried by said needle-valve having a fixed connection to the valve controlling the opening between the vaporizing and air chambers, means located between said arm and said valve to hold the latter to its seat, a gasolene-reservoir encompassing said vaporizing and air chambers, a float carrying a tapering valve to control the feed-supply to said reservoir, said stand-pipe communicating with said reservoirs, and an inlet-pipe communicating with said valve, substantially as and for the purpose set forth.

5. In a carbureter, a gasolene-reservoir

comprising an open-top cylindrical body having an indrawn bottom provided with a drainage-trap, a concentrically-disposed open-top chamber suspended within said reservoir and forming a part therewith by means of a uniting-web, an apertured diaphragm separating said chamber into an upper and a lower compartment, an exhaust-port leading through said web from said upper compartment, a waste-tube leading from said lower compartment through said reservoir, a stand-pipe communicative with said reservoir and passing through said compartments, a spray-nozzle leading from said stand-pipe and opening within said upper compartment, a valve to control said spray-nozzle, a valve operative on and adapted to vary the opening in said diaphragm, means to actuate both of said valves simultaneously, a cap to said reservoir, a float-controlled valve to supply said reservoir, and an inlet-pipe communicating with said float-valve, substantially as, and for the purpose set forth.

EARL E. ADAMS.
